(57) **CLAIM**

The ornamental design for a sectional sofa combination as shown and described.

DESCRIPTION

FIG. 1 is a front, right, top perspective view of a first component of a sectional sofa combination shown separately for ease of illustration;

FIG. 2 is a rear, left, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right, top perspective view of a second component of the sectional sofa combination shown separately for ease of illustration;

FIG. 10 is a rear, left, bottom perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a front, right, top perspective view of a third component of the sectional sofa combination shown separately for ease of illustration;

FIG. 18 is a rear, left, bottom perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a rear, right, top perspective view of a fourth component of the sectional sofa combination shown separately for ease of illustration;

FIG. 26 is a front, left, bottom perspective view thereof;

FIG. 27 is a front elevational view thereof;

FIG. 28 is a rear elevational view thereof;

FIG. 29 is a left side elevational view thereof;

(Continued)

FIG. 30 is a right side elevational view thereof;
FIG. 31 is a top plan view thereof;
FIG. 32 is a bottom plan view thereof;
FIG. 33 is a front, left, top perspective view of a fifth component of the sectional sofa combination shown separately for ease of illustration;
FIG. 34 is a rear, right, bottom perspective view thereof;
FIG. 35 is a front elevational view thereof;
FIG. 36 is a rear elevational view thereof;
FIG. 37 is a left side elevational view thereof;
FIG. 38 is a right side elevational view thereof;
FIG. 39 is a top plan view thereof;
FIG. 40 is a bottom plan view thereof;
FIG. 41 is a front, left, top perspective view of a sixth component of the sectional sofa combination shown separately for ease of illustration;
FIG. 42 is a rear, right, bottom perspective view thereof;
FIG. 43 is a front elevational view thereof;
FIG. 44 is a rear elevational view thereof;
FIG. 45 is a left side elevational view thereof;
FIG. 46 is a right side elevational view thereof;
FIG. 47 is a top plan view thereof;
FIG. 48 is a bottom plan view thereof;
FIG. 49 is a perspective view of the first configuration, consisting of the first component, the second component, the third component, the fourth component, the fifth component, and the sixth component, assembled together;

FIG. 50 is a perspective view of the second configuration, consisting of the first component, the third component, the fifth component and the sixth component, assembled together; and,

FIG. 51 is a perspective view of the third configuration, consisting of the first component, the third component, the fourth component, the fifth component, and two sixth components, assembled together.

The broken lines in the drawings depict portions of the sectional sofa combination that form no part of the claimed design.
